NONSLIP SHOELACE DEVICE

Carmine Panza, Bronx, N. Y.

Application December 31, 1943, Serial No. 516,501

8 Claims. (Cl. 24—117)

This invention relates to new and useful improvements in a non-slip shoelace device.

More particularly, the invention contemplates the association of a leaf spring with an eyelet for a lace, arranged to releasably hold the shoelace from slipping. This construction has numerous advantages. The shoe laces on shoes are continually becoming loose while walking, requiring frequent adjustments. While the invention is particularly intended for shoes, it may be used for other articles wherever laces are used, as for example, corsets and other garments.

The invention also proposes numerous modifications one of which includes means for holding the leaf spring in a lifted position so that the lace may freely pass, when this is desired.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a shoe constructed in accordance with this invention.

Fig. 2 is a fragmentary plan view of a portion of Fig. 1 showing the details of one of the eyelets.

Fig. 3 is a fragmentary enlarged vertical sectional view taken on the line 3—3 of Fig. 2.

Fig. 4 is a view similar to Fig. 2 but illustrating a modified construction.

Fig. 5 is an enlarged vertical sectional view taken on the line 5—5 of Fig. 4.

Fig. 6 is a perspective view of the slide shown in Figs. 4 and 5.

The non-slip shoelace device, in accordance with this invention, includes an eyelet 10 for a lace 11. This eyelet has a friction gripping portion 12. A leaf spring 13 is mounted on the eyelet 10 and is directed towards said friction gripping portion 12 for forcing and clamping said lace against said gripping portion.

The leaf spring 13 is attached at one of its ends 14 to one of the flanges 15 of the eyelet 10. A rivet 16 serves for this attachment, though these parts may be connected in other ways. The leaf spring 13 extends through the eyelet 10 and over a section of the lace 11. The top end of the leaf spring 13 is formed with serrations 17 which engage the lace 11 and press it against the roughened friction gripping portion 12.

In Fig. 1 a shoe 17' is illustrated provided with customary eyelets 18. However, the top eyelet, indicated by reference numeral 18', is of the im-

proved construction. This shoe is shown having said lace 11 in position, laced through all eyelets.

The operation of this form of the invention is as follows:

The lace 11 is engaged through the eyelet in the usual way. It is drawn tight and the serrations 17 will press the lace against the roughened portion 12 for gripping same and holding it from slipping back. The lace is tied in the usual way.

When it is desired to remove the shoe, the lace is first untied. Then the leaf spring 13 is lifted up with the fingers so that the lace 11 is freed, and then it is pulled through the eyelet.

In Figs. 4—6 a modified form of the invention has been disclosed which is very similar to the first form of the invention, distinguishing merely in the fact that a slide 20 has been mounted on the leaf spring 13 and is associated with certain holding means by which the leaf spring 13 may be held in an inoperative position. The leaf spring 13 is shown attached to the eyelet 10' by welded points 21 and 22. The slide 20 has finger-like portions 23 projecting from its sides. These finger-like portions 23 are engageable behind certain hook-like projections 24 formed along the sides of the top flange of the eyelet 10'.

The operation of this form of the invention is identical to the prior form, except that when it is desired to free the lace 11, the slide 20 may be moved back on the leaf spring 13 so that the fingers 23 engage behind certain of the projections 24 and hold the leaf spring 13 in a raised position. The lace is now free.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A non-slip shoelace device, comprising an eyelet for a lace and having a friction gripping portion, and a leaf spring mounted on said eyelet and directed towards said friction gripping portion for forcing and clamping said lace against said gripping portion.
2. A non-slip shoelace device, comprising an eyelet for a lace and having a friction gripping portion, and a leaf spring mounted on said eyelet and directed towards said friction gripping portion for forcing and clamping said lace against said gripping portion, said gripping por-

tion being in the nature of a roughened area on said eyelet.

3. A non-slip shoelace device, comprising an eyelet for a lace and having a friction gripping portion, and a leaf spring mounted on said eyelet and directed towards said friction gripping portion for forcing and clamping said lace against said gripping portion, said leaf spring being mounted at one of its ends upon a side portion of the eyelet and extending through the eyelet to the top.

4. A non-slip shoelace device, comprising an eyelet for a lace and having a friction gripping portion, and a leaf spring mounted on said eyelet and directed towards said friction gripping portion for forcing and clamping said lace against said gripping portion, said leaf spring being riveted on the flange of said eyelet.

5. A non-slip shoelace device, comprising an eyelet for a lace and having a friction gripping portion, and a leaf spring mounted on said eyelet and directed towards said friction gripping portion for forcing and clamping said lace against said gripping portion, said leaf spring being welded on the flange of said eyelet.

6. A non-slip shoelace device, comprising an eyelet for a lace and having a friction gripping portion, and a leaf spring mounted on said eyelet

and directed towards said friction gripping portion for forcing and clamping said lace against said gripping portion, said leaf spring having a serrated end cooperative with said friction gripping portion for gripping and holding said lace.

7. A non-slip shoelace device, comprising an eyelet for a lace and having a friction gripping portion, and a leaf spring mounted on said eyelet, directed towards said friction gripping portion
10 for forcing and clamping said lace against said gripping portion, a slide mounted on said leaf spring, and means for releasably connecting said slide with said eyelet for holding said leaf spring in an elevated inoperative position.

15 8. A non-slip shoelace device, comprising an eyelet for a lace and having a friction gripping portion, and a leaf spring mounted on said eyelet, directed towards said friction gripping portion for forcing and clamping said lace against said gripping portion, a slide mounted on said leaf spring, and means for releasably connecting said slide with said eyelet for holding said leaf spring in an elevated inoperative position, said means including finger portions projecting from said slide and engaging behind projections along the sides of said eyelet.

CARMINE PANZA.
